UNITED STATES PATENT OFFICE

113,469

DESIGN FOR AN ABBREVIATED SHIRT

James E. Washington, Portsmouth, Va.

Application December 30, 1938, Serial No. 82,087

Term of patent 14 years

To all whom it may concern:

Be it known that I, James E. Washington, a citizen of the United States of America, residing at Portsmouth, county of Norfolk, State of Virginia, have invented a new, original, and ornamental Design for an Abbreviated Shirt, of which the following is a specification, reference being had to the accompanying drawing, wherein:

I claim:

The ornamental design for an abbreviated shirt, as shown.

JAMES E. WASHINGTON.
